COMBUSTION APPARATUS

John W. Miller and Vaughn H. Hill, Lansing,
Mich., assignors to Motor Wheel Corporation,
Lansing, Mich., a corporation of Michigan

Application October 14, 1939, Serial No. 299,470

4 Claims. (Cl. 158—91)

This invention relates to combustion apparatus of the vaporizing pot type, and resides primarily in the construction and arrangement of the parts of the burner proper.

It is the primary object of the present invention to provide a burner for apparatus of the character mentioned above which will produce a clean and stable fire throughout substantially its entire range of operation, that is to say, at various rates of oil consumption. This object is attained by introducing part of the primary air to the burner through spaced air inlet openings formed in the side wall of the burner and the remainder through spaced air inlet openings formed in an air tube disposed centrally of the burner, and by associating a series of baffle rings with the central air tube which extend radially outwardly therefrom toward the side wall of the burner. The peripheries of the baffle rings terminate short of the side wall of the burner and are all positioned below the lowermost primary air inlet openings formed in the side wall of the burner.

By this construction and arrangement of parts eddy currents are substantially eliminated in the lower part of the burner and the premixture of air and oil vapors produced during the operation of the burner at its higher stages is delivered to the upper part of the burner adjacent the side walls thereof, rather than in the center thereof, as in conventional constructions. As a consequence, clean and stable combustion is produced throughout substantially the entire range of operation.

Other objects more or less ancillary and incidental to the foregoing will become apparent from a reading of the following specification, taken in connection with the accompanying drawing, wherein—

Figure 1 is a vertical sectional view of a space heater embodying the present invention; and

Figure 2 is a cross-sectional view taken on the line 2—2 of Figure 1.

The space heater shown in Figure 1 includes a cylindrical casing 10 closed at its upper extremity by a top wall 11 and supported at its lower extremity by a pair of crossed supporting straps 12 and 13 which are formed at their opposite extremities to provide legs 14.

The upper portion of the casing 10 forms a combustion chamber 15 and a lower portion forms an air compartment 16 adapted to receive a burner 17. The present invention, as previously stated, resides in the construction and

arrangement of the burner parts, and these will be described in detail presently.

Access is had to the combustion chamber 15 through a door 18 opening in the front thereof. The door 18 also serves to provide means for introducing a lighted taper into the apparatus to initially ignite the oil. The products of combustion are withdrawn from the combustion chamber 15 through a flue outlet 19 having one end associated with the upper portion of the combustion chamber 15 and its other end communicating with a chimney 20. The flue outlet 19 is preferably provided, as shown, with an automatic draft regulator 21 whereby to maintain a constant draft on the apparatus. It will of course be apparent that the air compartment 16, in which the burner 17 is located, is open to the atmosphere by reason of the supporting straps 12 and 13 previously mentioned.

The burner 17 includes a bottom wall 22, a side wall 23, a top wall 24, an anti-explosion baffle 25, a central air tube 26, and a plurality of vertically spaced apart baffle rings 27 extending radially outwardly from the central air tube 26. The top wall 24 is provided with a large central opening 24a. The side wall 23 of the burner 17 is formed adjacent its upper extremity to provide a radially outwardly extending annular rib 28 and a radially inwardly extending annular rib 29 therebelow. The top wall 24 is supported upon the radially inwardly extending annular rib 29. The anti-explosion baffle 25 is positioned above and supported by the top wall 24. The bottom wall 22 is provided with a central opening with which is associated the central air tube 26. The latter is closed at its upper extremity and open to the atmosphere at its lower extremity.

Air is supplied to the apparatus through primary and secondary air inlet openings. The primary air inlet openings are arranged in two groups. One group is formed in the side wall 23 of the burner below the top wall 24 and consists of a plurality of vertically spaced horizontal rows of openings 30, the openings in each row being spaced circumferentially. The other group is formed in the side of the central air tube 26 and consists of a plurality of vertically spaced horizontal rows of openings 31, the openings in each row being spaced circumferentially.

The air inlet openings 31 formed in the side of the central air tube 26 are arranged with respect to the baffle rings 27 so that there are two rows of openings below the lowest baffle ring and

two rows of openings between each pair of adjacent baffle rings.

The secondary air inlet openings 32 are formed in the side wall 23 of the burner above the top wall 24 and below the anti-explosion baffle 25. They are located in the lower leg of the radially outwardly extending annular rib 28 whereby the air admitted therethrough is directed inwardly and upwardly. The anti-explosion baffle 25 and the secondary air inlet openings 32 are constructed and arranged with the axis of the openings intersecting the horizontal plane of the baffle whereby the air admitted through the secondary air inlet openings impinges against the baffle.

All of the primary and secondary air inlet openings are in communication with the lower part of the casing forming the air compartment 16 and through it with the atmosphere. Consequently, both the primary and secondary air is drawn into the apparatus by means of the draft communicated to the apparatus from the chimney. By reason of the fact that the peripheries of the baffle rings 27 associated with the central air tube 26 are located below all of the primary air inlet openings 30 formed in the side wall 23 of the burner, the air from the primary air inlet openings 31 formed in the side of the central air tube 26 is directed toward the side wall 23 of the burner at a level below the level of the primary air inlet openings 30 formed in the side wall of the burner. Preferably, the size and number of the air inlet openings are such that a greater volume of air is admitted to the apparatus through the primary air inlet openings 30 and 31 than through the secondary air inlet openings 32.

Provision is made for supplying oil to the burner in regulatable quantities from a source of supply not shown through a supply pipe 33 with which there is associated a conventional regulating valve 34. As shown, the bottom wall 22 of the burner is formed to provide a well or sump 35 into which the oil flows from the supply pipe 33.

To facilitate mounting the burner 17 within the casing 10, the latter is provided with a radially inwardly extending annular shoulder 36 between the upper and lower portions of the casing. The burner is mounted within the casing with the radially outwardly extending burner rib 28 engaging the radially inwardly extending casing rib 36, and is secured in that position by means of a plurality of adjustable screw elements 37 threadedly mounted in the straps 12 and 13 and the free extremities of which engage the bottom of the burner. The straps 12 and 13 are secured to the inturned flange 38 at the lower extremity of the casing 10 by means of bolts 39.

The operation of the combustion apparatus herein shown and described is as follows:

The valve is opened and oil flows into the burner. The oil is ignited by inserting a match or lighted taper through the door and dropping it onto the bottom of the burner. Initially, and so long as oil is admitted to the burner in limited quantities only, combustion will occur in the lower part of the apparatus below the baffle rings. As the rate of flow of oil is increased the zone in which combustion is initiated rises within the apparatus until at the maximum flow of oil the lower limit of the zone of combustion will be localized adjacent the top of the burner in the region of the central opening in the top wall. The anti-explosion baffle prevents the lower limit of the zone of combustion from rising above that

point in a well known manner, thereby eliminating the possibility of explosions. As is well known, it is an inherent characteristic of the present apparatus that the lower limit of the zone of combustion may be localized at substantially any desired point between the bottom of the burner and the top of the burner by proper adjustment of the regulating valve.

When combustion is located in the lower part of the burner, the baffle rings prevent the formation of eddy currents which otherwise would interfere with the stability, and therefore, with the cleanliness of the burner. In the higher stages of operation, the premixture of oil vapors and air produced in the lower part of the burner is delivered to the upper part adjacent the side walls thereof whereby until the highest stage of operation is reached the lower limit of combustion is localized in the region of the side wall of the burner. This assures direct radiation of heat to the bottom of the burner, and also conduction of the heat to the bottom of the burner through the side wall to an extent sufficient to maintain adequate vaporization of oil.

It will, of course, be understood that at the higher stages of operation objectionable eddy currents which would interfere with stability of operation are prevented by the top wall.

The scope of the invention is indicated in the appended claims.

We claim:

1. Combustion apparatus comprising a burner of the vaporizing pot type having a bottom wall with a central aperture therein and a side wall with a plurality of vertically and horizontally spaced apart air inlet openings therein at a substantial distance above the bottom wall; an upstanding tube within the burner, said tube being closed at its upper end and having an open lower end communicating with the aperture in the bottom wall of the burner, said tube having a plurality of vertically and horizontally spaced apart air inlet openings formed therein, and a baffle ring surrounding the tube and engaging the side thereof above the uppermost of the air inlet openings therein, the periphery of said baffle ring being spaced from the burner side wall and positioned below the lowermost air inlet openings in the burner side wall.

2. Combustion apparatus comprising a burner of the vaporizing pot type having a bottom wall with a central aperture therein, and a side wall with a plurality of vertically and horizontally spaced apart air inlet openings therein at a substantial distance above the bottom wall; an upstanding tube within the burner, said tube being closed at its upper end and having an open lower end communicating with the aperture in the bottom wall of the burner, said tube having a plurality of vertically and horizontally spaced air inlet openings formed therein, and a plurality of vertically spaced baffle rings surrounding the tube and engaging the side thereof, said baffle rings being spaced apart sufficiently to include some of the last mentioned air inlet openings between them the uppermost baffle ring being above the uppermost opening in the tube, the peripheries of said baffle rings being spaced from the burner side wall and positioned below the lowermost air inlet openings in the burner side wall.

3. Combustion apparatus comprising a burner of the vaporizing pot type having a bottom wall with a central aperture therein and a side wall with a plurality of vertically and horizontally spaced apart air inlet openings therein at a substan-

tial distance above the bottom wall; an upstanding tube within the burner, said tube being closed at its upper end and having an open lower end communicating with the aperture in the bottom wall of the burner, said tube having a plurality of vertically and horizontally spaced apart air inlet openings formed therein, a baffle ring surrounding the tube and engaging the wall thereof above the uppermost of the air inlet openings therein, the periphery of said baffle ring being spaced from the burner side wall and positioned below the lowermost air inlet openings in the burner side wall, and a top wall for the burner, said top wall having a large central aperture therein and located below the topmost air inlet openings in the burner side wall.

4. Combustion apparatus comprising a burner of the vaporizing pot type having a bottom wall with a central aperture therein, and a side wall

5 with a plurality of vertically and horizontally spaced apart air inlet openings therein at a substantial distance above the bottom wall; an upstanding tube within the burner, said tube being closed at its upper end and having an open lower end communicating with the aperture in the bottom wall of the burner, said tube having a plurality of vertically and horizontally spaced apart air inlet openings formed therein, and a downwardly diverging frusto-conical baffle ring surrounding the tube and engaging the side thereof above the uppermost of the air inlet openings therein, the periphery of said baffle ring being spaced from the burner side wall and positioned below the lowermost air inlet openings in the burner side wall.
